MINOR B. STYER, OF DAYTON, KENTUCKY

DESIGN FOR A BRACELET OR SIMILAR ARTICLE OF JEWELRY

Application filed October 29, 1930. Serial No. 37,424. Term of patent 7 years.

To all whom it may concern:

Be it known that I, MINOR B. STYER, a citizen of the United States of America, residing at Dayton, in the county of Campbell and State of Kentucky, have invented a new, original and ornamental Design for a Bracelet or Similar Article of Jewelry, of which the following is a specification, reference being had to the accompanying drawing, forming a part thereof.

I claim:—

The ornamental design for a bracelet or similar article of jewelry as shown.

MINOR B. STYER.
